UNITED STATES PATENT OFFICE

2,491,517

LIQUID FUEL BURNING APPARATUS

Milton A. Powers and Noel H. Sutterfield, Detroit,
Mich., assignors to The Timken-Detroit Axle
Company, Detroit, Mich., a corporation of Ohio

Original application May 27, 1941, Serial No.
395,464. Divided and this application July 17,
1944, Serial No. 545,234

10 Claims. (Cl. 158—4)

1

This invention relates to oil burning apparatus of the rotary wall flame type, and more particularly to water heaters of small capacity for smaller homes embodying oil burners of the general type shown in United States Letters Patent to Sutterfield No. 2,102,763 and to Wilson and Sutterfield No. 2,310,333, and is a division of our application Serial No. 395,464 filed May 27, 1941, which issued October 24, 1944, as United States Letters Patent No. 2,360,891.

We have discovered that by employing a fan having adequate volumetric capacity to support combustion but delivering air at sufficiently restricted velocity to insure efficient ignition, and at the same time avoiding excessive recirculation, in combination with a grill assembly designed to deflect the flame behind the flame rim, and a flame shield to prevent the combustion gases from making direct contact with the cold portion of the water backed surfaces, it is possible to successfully use smaller diametered hearths and to efficiently burn fuel at lower rates than have heretofore been considered feasible with a rotary wall flame type burner.

It is accordingly the primary object of our invention to provide a small novel oil burning water heating apparatus capable of efficiently burning extremely small quantities of oil, thereby to make it practical for medium sized and small homes having limited space and money for such facilities.

A further object of our invention is to provide a heating unit embodying an oil burner of the rotary wall flame type in which the hearth and combustion chamber are completely suspended in the cabinet member and efficiently insulated against heat loss.

A further object of our invention is to provide a fan or air distributing device having sufficient capacity to efficiently pump the required amount of air for combustion and which is so designed as to avoid imparting sufficient velocity to the air to interfere with ignition, even when an extremely small hearth is used, and at the same time is also designed to avoid excessively recirculating hot gases of combustion.

A further object is to provide a small rotary wall flame type water heating oil burner with a novel hearth flame rim, grille and shield assembly which makes it possible to efficiently utilize smaller diameter and/or capacity combustion chambers than have been heretofore regarded as practicable.

A still further object is to provide improvements in oil burner controls of the trip-bucket

2

type, which eliminate the inconvenience of unnecessary trippings, and still insure safety of control, and to also provide improved means for tilting the hearth surface toward the overflow port.

Further objects are to generally improve and refine certain subordinate features of heating apparatus, which will become apparent as the specification proceeds in conjunction with the annexed drawings, and from the appended claims.

In the drawings:

Figure 1 is a vertical sectional view of a heating apparatus embodying the invention.

15 Figure 2 is a vertical sectional view on an enlarged scale of the lower part of the apparatus shown in Figure 1, and illustrates the hearth and distributor assembly.

Figure 2a is a fragmental elevational view of 20 the ignitor shown in Figure 2, as it appears when viewed from the right-hand side of that figure.

Figure 3 is a fragmental top plan view of the 25 hearth and distributor assembly shown in Figure 2.

Figure 4 is a bottom plan view of the fan shown 30 in Figures 2 and 3, and illustrates the relationship assumed by the oil flinger tubes with respect to the fan blades.

Figure 5 is a sectional view of the lower part 35 of the casing shown in Figure 1, taken substantially along the line 5—5 of that figure.

Figure 6 is a view similar to Figure 2, but illustrates a modified form of hearth assembly, also forming part of the invention.

35 Figure 7 is a fragmental sectional view on a greatly enlarged scale, of the edge of the overflow port shown in Figure 6.

With continued reference to the drawings, wherein like reference characters have been employed to designate like parts throughout the several views thereof, the heating apparatus of the invention comprises a cabinet member A, in which is suspended a shell-like combustion chamber B and also a hearth assembly C, which in turn supports a liquid fuel burning apparatus designated generally as D.

Cabinet structure

The cabinet structure is made up of a base member 10 having a bottom rim 11, and adjacent its upper edge are provided a plurality of circumferentially spaced brackets 12. The cabinet structure proper, designated as 13, is telescoped within base member 10 at its lower edge and rests 50 upon brackets 12. The parts may be secured in

overlapped assembled relationship by nut bolt assemblies 14.

The lower front portion of the cabinet is provided with a service opening 15, which is closed by a door 16 having a handle 17 in the form of a knurled headed bolt threaded into a nut welded to the inner face of the casing. Each side of the door, at its lower edge, is provided with a clip member 18, which fits inside base member 10, and the latter is provided with a single upstanding retaining member 19, located adjacent the middle of the door, which prevents the mid-portion of the door from bowing inwardly, when it is disposed in the abutting relationship to the upper edge of member 10 shown in Figure 1.

The base is also preferably provided with a plurality of levelling screws 20 threaded into brackets 21 secured to the inner wall of the base and locked in place by lock nuts 22.

Cabinet 13 has a plurality of brackets 24' for supporting the base plate and the combustion chamber, as hereinafter set forth in detail, which are secured at circumferentially spaced points around the interior of the cabinet structure, and a bracket 23 for supporting a transformer T, all of which are attached as by spot welding. A plate 24 is secured to the transformer and is hooked under a lip provided on bracket 23. The plate and bracket are secured together at their lower edges by bolts 25. Although the cabinet has been illustrated as a circular section, it is to be understood that it may be of rectangular or other shape in section without departing from the spirit of the invention.

The top of the cabinet is closed by means of a member 26 having a flange 27 fitting tightly over the upper edge of the cabinet. A plate 28, terminating inwardly of flange 27, is secured in spaced relationship to the under side of closure 26 by means of a plurality of brackets 29, and the space between the two members is filled with a blanket of insulating material 31 of any suitable character.

The cabinet top also embodies a combined baffle and inspection assembly of novel form. Supported in spaced relationship below the top, by means of a plurality of brackets 30, is a baffle 30a, which is operable to divert the hot products of combustion around the upper convolutions of the coil, and prevent escape to the flue until they have transmitted substantially all of the available heat to the coil, as will hereinafter appear.

The baffle is provided with a preferably eccentrically located inspection opening 30b of restricted size, while cover 26 is provided with a concentrically located inspection opening 32, closed by a hinged cover 33 or the like. By opening cover 33 the operation of the burner may be observed through openings 30b and 32, and because of the location of opening 32 this may be done without permitting excess air to enter near the base of the flame and interfere with combustion. Also, because of the eccentricity of opening 30b, the cover may be rotated so as to progressively bring the entire hearth into view, the field of vision for one position of the cover being indicated by dotted lines in Figure 1.

The rear wall of the cabinet adjacent the top, is provided with a flue pipe opening 34, which extends completely to the upper edge of the cabinet, so that when the top is removed it presents an open-sided recess. The back of the cabinet is also provided with a pair of openings 35 and 36, through which the outlet and inlet connections

respectively of the coil project, as will hereinafter appear.

Combustion chamber assembly

The combustion chamber proper comprises a cylindrical shell 41 of sheet metal having its ends butted at 42 and secured together in any suitable manner such as by welding. The combustion chamber fits within the cabinet and is so dimensioned as to provide a space 43 between the walls thereof, and which is preferably completely filled with a blanket of insulating material 44.

Secured to the outside of the combustion chamber adjacent its lower end, as by welding or the like, are a plurality of bracket members 45 which are preferably so spaced as to seat upon every other bracket 24', although it is to be understood that if desired they may be made equal in number to, and seat upon, all of brackets 24'. Brackets 45 are secured in place on brackets 24' by a plurality of screws 46 and nuts 47. A hearth assembly is also supported upon screws 46 as in a manner to be hereinafter described.

As seen in Figure 1, plate 28 overlaps the upper edge of combustion chamber 41, but terminates short of the walls of cabinet 13, so that the insulation in the top of closure member 26 may contact directly with the insulation 44 between the cabinet and the combustion chamber walls. To insure proper spacing of the combustion chamber from the walls of the cabinet a plurality of spacer members 49 are preferably secured to the combustion chamber and fit closely against the cabinet walls to maintain the parts in properly spaced relationship.

Disposed within combustion chamber 41, in proximity to the internal wall thereof, is a cylindrical helically wound water heating coil 50, preferably of copper, and is supported in fixed relation thereto by means of an inlet fitting 51 and an outlet fitting 52, both of which are secured to the combustion chamber as by cap screws 53. As seen in Figure 1, each fitting is provided with a short neck 54 which projects through an opening in the combustion chamber and to which is threaded secured a pipe nipple 55. The latter are connected to the domestic hot water or heating radiator lines in well known manner.

An opening 56 is provided adjacent the top of the combustion chamber and secured in alignment therewith, is a flanged flue connecting member 57, by a pair of nut and bolt assemblies 58. Flue connection 57 extends through the insulation and opening 34 out of the cabinet to a usual flue pipe (not shown) in well known manner. In assembling, the chamber may be lowered as a unit into the cabinet with member 57 in place, by reason of the shape of opening 34, after which the connections which maintain the combustion chamber in place are connected.

Hearth structure

The entire hearth assembly is carried in novel manner by a foundation or base plate 61, which has a diameter slightly greater than the combustion chamber, and is also preferably supported by brackets 45. Although, if desired, only a few brackets 24' may be utilized for supporting the combustion chamber and hearth assembly, preferably all of the bolts 46 extend through openings in the base plate 61, and nuts 62 are threaded thereon to hold the base plate in place.

A layer of insulating material 64 is mounted on the base plate, and when nuts 62 are turned home the peripheral edge of the insulation 64 is

clamped in air-tight engagement with the lower edge of the combustion chamber. Base plate 61 may be either embossed so that the hearth, supported thereby by supports 71 of equal length, will incline from the horizontal, or the lower edge of the combustion chamber may be so shaped as to lie in a plane inclined to the horizontal, so that when the base plate is pulled into assembled relationship it will assume a similar inclination. Either alternative eliminates the necessity for specially designing the hearth to drain any overflow oil to one side. In the construction shown in Figure 1 the entire base plate is inclined by reason of an inclined edge provided on chamber 41.

As seen in Figure 2, the base plate is approximately centrally apertured. Disposed in alignment therewith is a spacer collar 66 which supports the central portion of an apertured metal hearth 67 in spaced relation to the base plate. The hearth and collar are secured to the base plate by a sleeve 68 which is flanged over the hearth and base plate at its upper and lower ends respectively. The outer edge of the hearth is provided with an upstanding flange 69, to which is secured a plurality of supporting legs 11, which extend through openings 72 in the insulation and rest upon the upper surface of the base plate, to which they are attached as by welding.

Mounted in spaced relation to each other on the hearth is an annular flame rim having an oil atomizing and vaporizing wall 73 and an air deflecting wall 74, which are welded to a plurality of U-shaped brackets 75, and the latter are welded to the hearth, so as to form a rigid unitary assembly. Also rigidly secured to the hearth is a shield ring 76, which snugly fits inside flange 69 and may be welded thereto if desired.

At one side of the hearth is provided an igniter of novel construction, comprising an electrode 77, having an outwardly projecting portion 77a, which is disposed in sparking relationship to the inner face of wall 73, and is disposed at a predetermined angle with respect to a radius drawn through the center of the hearth, preferably 25 degrees, as indicated in Figure 3. The electrode is eccentrically mounted in an insulator 78 of generally cylindrical form. The latter is frictionally gripped in a bracket 78a carried by the base plate. The hearth adjacent the insulator 78 is flanged up as at 79 to prevent any excess oil from leaking down between the insulator and hearth.

By mounting the electrode in an igniter insulator having an eccentric aperture, and mounting the insulator for rotative adjustment, a fixed angle of incidence and a predetermined gap may be maintained despite manufacturing tolerances and burning or wear. For instance, if the gap becomes too large, insulator 78 may be rotated slightly in its bracket, to move the electrode closer toward wall 73. If this results in swinging portion 77a materially away from the desired angle, proper relationship of the parts may be restored by loosening a pair of nuts 79a and rotating the electrode within a clip 79b, which engages flat portions provided on opposite sides of the insulator. When the adjustment is completed, nuts 79a are then tightened, which pulls the clip into tight engagement with a shoulder 79c provided on the electrode.

The igniter is connected to the high tension circuit of the transformer in any well known manner. Located at the low side of the hearth, preferably opposite the igniter, is a pair of recesses

or circular channels 80 and 81 which surround an outlet port 82. Outlet port 82 communicates with a pipe 83 supported by a bracket 84 below the hearth, which leads to a trip bucket type of automatic shut-off mechanism S so that after a predetermined quantity of oil passes through pipe 83 the bucket will be tripped and the burner automatically shut off. Mechanism S projects through an opening in the casing and is preferably supported on a bracket assembly 84a carried by plate 61.

Channels 80 and 81 perform the highly important function of trapping any oil discharge which is not immediately ignited at the time the burner starts. This prevents a flow of oil through pipe 83 into the trip bucket on "cold" start. As previously pointed out, the foundation plate is inclined, which produces a corresponding slope of the hearth toward outlet 82, so that in the event of failure of the ignition, the overflowing oil will pass through the discharge port into pipe 83, and cause the shut-off mechanism to stop the burner motor. In the past some difficulty has been experienced in having small dribbles of oil on cold or slow starts dripping into the drip bucket and eventually tripping the bucket, despite the fact that no more than normally cold starts have occurred, and no occasion has arisen for the shut off of this character.

With the novel constructions herein disclosed, any oil accumulating in channels 80 and 81 during cold starts, and which is not immediately ignited, is under normal conditions burned off during the ensuing normal operating cycle of the burner, with the result that no oil whatever enters the trip bucket.

Grille structure

A further important feature of the invention resides in an improved grille structure, which, particularly when employed in combination with the novel distributor of the invention and shield 76, greatly assists in enabling the burner to operate at extremely low rates of oil consumption, and in combustion chambers of smaller size than heretofore regarded practical.

The grille ring shown in Figures 2 and 3 comprises a simple cylindrical band of heat resistant sheet metal 85 having its ends overlapped and secured together, and a plurality of similarly shaped channel members 86. Each of the channel members is secured to or integral with the outer face of ring 85, preferably with the open sides of the channels facing downwardly. As seen in Figure 3, the channels are disposed in symmetrical, radiating relationship to ring 85 and are supported approximately at their mid-portions by wall 73. Although the channels may be secured to the flame rim, the grille assembly preferably merely freely rests upon the flame rim, so that any thermally induced expansion or contraction of the parts may take place freely. Also, it enables the grille ring to be inverted, so as to face the channels upwardly, depending upon the arrangement which is found to work best under the particular condition at hand. The channels preferably open downwardly in the particular small capacity unit illustrated, so as to cause the flame to pass outwardly along the channels and then behind wall 73, and to maintain a zone of rapid and efficient combustion between band 73 and shield 76, and to also maintain the flame rim at an efficient fuel vaporizing temperature. Reversibility of the grille is particularly desirable when the lower grades of fuel oil are burned.

The function of any grille is to assist mixing of the air and oil projected from the distributor head and to prevent the flame from lifting above the flame rim to a height where it will not heat the flame rim sufficiently to vaporize the oil projected against it. In the small heating unit illustrated, the distance between the ends of the distributor tubes, to be hereinafter described, and the flame rim is comparatively short, approximately $2\frac{1}{8}$ inches. With the rim in such close proximity to the flinger tubes it was found impossible for the older type of grilles to properly mix the air and oil for complete and clean combustion without circulating a large amount of the hot gases of the combustion. Excessive recirculation is undesirable, especially in the small hot water heater because there may be many numerous cold starts, particularly during the summer season, and on a cold start the effect of excessive recirculation is to cause an excessive flow of cold, fresh air, which at high velocity may retard rather than assist ignition of the fuel. We have found that by so designing the fan as to produce a limited degree of recirculation, with sufficient volume to combust the fuel and at sufficiently low velocity to avoid delaying ignition, as will be described hereinafter, and providing the grille assembly constructed as just described, which deflects the gases of the combustion flame behind the flame rim under all normal conditions, and using a shield 76 to prevent contact of the flame with the lower portion of the coil, the apparatus performs with complete satisfaction.

Distributor

The distributor comprises a motor and pump unit 88, which is preferably constructed substantially as disclosed in Wilson and Sutterfield Patent No. 2,310,333. The unit as illustrated, however, is supported by two studs 90 which pass through brackets 91a secured to the bottom of the motor housing and have wing nuts 90b threaded thereon. The motor is provided with a shaft 89 upon which is supported an oil distributing head 91. A pair of upwardly and outwardly extending oil tubes 92, carried by head 91 are designed to propel the oil in the form of unatomized droplets in a trajectory located above the blast from the fan, against the inner face of wall 73, with sufficient velocity to shatter or atomize them.

Secured to the upper end of shaft 89, by means of a set screw 93, is a hub member 94, to which is welded a fan head or disc 95.

Secured to the underside of head 95 are a plurality of flanged blades 96 and 97, which are preferably equally spaced. Blades 96 are preferably six in number and will be termed the "pumping" blades since they are comparatively short and function primarily as pumping blades. Blades 97 are two in number and extend beyond the periphery of the head and will be hereinafter termed "velocity blades."

It was found that the earlier designs of fans, having many long velocity blades, imparted too great velocity to the air, which rendered ignition, particularly on a cold start, extremely difficult. Further, in a small combustion chamber and hearth assembly as employed in the present construction, a high air velocity tends to induce excessive recirculation. The novel fan assembly just described overcomes this difficulty because the greater number of short pumping blades assures sufficient air for combustion without excess velocity, and by locating the distributor tubes leeward of the velocity blades the tubes

are maintained out of contact with the heated recirculated gases that are inevitably drawn into the fan and are discharged along the leading faces of the blades with the fresh air supply.

To further insure against excessive recirculation by the tips of the oil tubes 92, and to also protect the tubes against excessive heating, cover 95 is provided with a short lip or skirt 98, and the ends of the flinger tubes are located closely adjacent the fan cover. Both of these features cooperate to prevent the recirculated gases from heating and carbonizing the oil in the ends of the distributor tubes.

Shield 76 is important in the small sized unit illustrated, because in such unit a number of critical factors are present. Although shields of various types have been before disclosed in the art, the only functions were to prevent the shielded parts from being subjected directly to the flame, and to prevent the cold water coils from chilling the flame and precipitating soot. It has been found that by making the shield 76 of the correct height it will deflect the hot gases of recirculation and combustion upwardly and away from the lower convolutions of the coil 50 and very good control over the hearth temperature can be maintained, in addition to realizing the decided advantage of preventing direct contact of the flame with the lower convolutions of the coil.

The illustrated construction is a commercial unit marketed by the assignee of this application and which has given complete satisfaction in all respects. The important dimensions of this unit are as follows, which are given by way of illustration and not limitation, it being understood that some latitude is permissible, depending upon the size of the hearth, the speed of the fan and other factors of the particular unit under consideration.

The hearth is approximately 10 inches in diameter and shield 76 is spaced approximately 2 inches from wall 41. Flame rim 73 is approximately 8 inches in diameter and one and one-half inches high, while shield 76 is three inches high. Grilles 86 are approximately one and one-half inches wide and one-fourth of an inch deep.

The fan is rotated at approximately 1600 R. P. M. The two sets of blades are of the same width and their inner ends all terminate approximately five-eighths of an inch from the axis of rotation. Blades 97 are approximately one and seven-eighths inches long, while blades 96 are approximately three-fourths of an inch in length.

In Figures 6 and 7 we have illustrated a modified form of heating apparatus also forming part of the invention. The major differences reside in the use of an embossed base, which automatically disposes the hearth at the proper inclination to effect drainage of oil, and a different form of overflow port, which is particularly useful where space does not permit use of the double groove construction shown in Figure 2.

A base plate 61a is secured in tight engagement with the lower edge of the combustion chamber as before. However, in this instance the lower edge lies substantially in a horizontal plane, and the plate, inwardly of its clamping edges, is embossed or formed so as to present an inclined portion 61 to which hearth supports 71 are secured. This construction accordingly makes it possible to utilize a combustion chamber having a square lower edge and hearth supporting legs of equal length, and yet supports the hearth 75 at the necessary inclination to effect proper

drainage of overflow oil. Also, if desired, insulation retaining members 102 may be secured to legs 71.

In this form of the invention a single oil drainage groove 103 is provided adjacent outlet 82a, and, as seen in Figure 7, the outlet is machined out at 104 to provide a sharp edge 105 over which the oil must discharge. We have found that, when using commercial grades of number 2 or number 3 fuel oil, the oil overflowing over the hearth will build up in groove 103 and form a meniscus 106, as shown in Figure 7, to a depth of approximately one-sixteenth of an inch above edge 105 before overflowing into opening 82a. As previously explained, any oil remaining in groove 103 after the burner is started will be consumed during the normal burning cycle, and the hearth will be dry when the burner is shut off.

Accordingly, by using a sharp edge adjacent the outlet port, the oil will build up to a depth sufficiently great to take care of all normal conditions, and yet it is unnecessary to employ a high wall to impound the oil.

From the foregoing it is apparent that the invention provides water heating apparatus of efficient and extremely simple and durable construction; and which, by reason of the novel assembly, when top 26 is removed, the interior of the cabinet and the combustion chamber are completely exposed, so that they may be inspected or serviced, and in the case of Figure 1, the entire coil may be thoroughly cleaned.

Also, by reason of the novel oil and air distributor, which supplies adequate air for combustion and yet is designed to effect a minimum recirculation of the combustion gases, in combination with novel grille assembly which insures adequate combustion behind the wall 73, it is possible to use a hearth and combustion chamber assembly of much smaller diameter than has heretofore been regarded as practicable in a wall flame burner.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. In a liquid fuel burning apparatus having means defining a combustion chamber; a centrally apertured refractory hearth in said combustion chamber and having a fuel atomizing and vaporizing wall located adjacent its periphery against which oil and air are adapted to be projected by a distributing device located in the aperture in said hearth; means providing an outlet in said hearth adapted to be coupled to a burner shut-off mechanism; the upper surface of said hearth being so sloped as to cause liquid oil to drain along said hearth toward said outlet; and recess means in said hearth surface adjacent said outlet for accumulating a predetermined quantity of oil before flow to said shut-off mechanism occurs.

2. In a liquid fuel burning apparatus having means defining a combustion chamber; a centrally apertured refractory hearth in said com-

bustion chamber and having a fuel atomizing and vaporizing wall located adjacent its periphery against which oil and air are adapted to be projected by a distributing device located in the aperture in said hearth; means defining an outlet port opening upwardly into the floor of said hearth and adapted to be coupled to a burner shut-off mechanism, the upper surface of said hearth being so sloped as to cause any overflow oil to drain along said hearth toward said outlet port; and means defining a recess in said hearth in surrounding relationship to said outlet port for accumulating a predetermined quantity of oil on said hearth before flow to said shut-off mechanism occurs.

3. The liquid fuel burning apparatus defined in claim 2, wherein said hearth, between said recess and said outlet port, is provided with a substantially continuous sharp edge so located as to cause the accumulating liquid fuel to build up to a predetermined depth above the level of said outlet port before discharging from said recess into said outlet port.

4. In a liquid fuel burning apparatus having means defining a combustion chamber; a centrally apertured refractory hearth in said combustion chamber and having a fuel atomizing and vaporizing wall located adjacent its periphery against which oil and air are adapted to be projected by a distributing device located in the aperture in said hearth; said hearth having a plurality of substantially continuous upper surface recesses therein located one inside the other; and means defining a discharge port opening into the upper surface of the hearth inside the innermost of said recesses, and said port having its upper edge at a higher level than the bottoms of said recesses.

5. In a liquid fuel burning apparatus having walls defining a combustion chamber, a hearth supported in said combustion chamber; a fuel atomizing and vaporizing wall extending around the periphery of said hearth and spaced from the interior of said combustion chamber and adapted to have liquid fuel and air projected toward it for combustion adjacent the upper edge thereof; an annular shield ring supported on said hearth in outwardly spaced and surrounding relation to said wall and extending a substantial distance above the top of said wall; and a flat narrow grill structure disposed within the confines of said shield ring comprising an annular member having a plurality of trough elements radiating outwardly therefrom, said trough elements resting on said wall to support said grill structure in the apparatus.

6. In a liquid fuel burner assembly adapted to be installed in a combustion chamber, a closure for the lower end of said chamber substantially centrally apertured to accommodate a rotatable fuel distribution head, a hearth mounted on said closure in surrounding relation to said head and having an annular upper surface sloping radially in opposite directions from its inner and outer peripheries, means defining a drain outlet port in said hearth at the lowermost region of said surface so that unburned liquid fuel deposited on said surface will drain toward said port, an annular flame rim surrounding said head mounted on said hearth in spaced relation to said head, an outer peripheral flange on said hearth spaced from said flame rim but within the confines of said combustion chamber, and an annular shield ring secured to said flange

and extending upwardly into the combustion chamber.

7. In the liquid fuel burner assembly defined in claim 6, said closure comprising a plate inclined at an angle with respect to the horizontal, and said hearth being attached to said plate.

8. In a liquid fuel burning apparatus having means defining a combustion chamber, a centrally apertured hearth disposed in the lower end of said chamber, an annular flame rim mounted on said hearth surrounding the aperture in said hearth and adapted to be impacted by liquid fuel projected outwardly by a rotating fuel distributing head extending upwardly through the aperture in said hearth, means providing a drain port on one side of said hearth, means mounting said hearth in said chamber in such inclined relation to the horizontal that liquid fuel deposited on the upper surface of said hearth will drain therealong toward said port, and a recessed hearth region about said drain port in the path of liquid fuel tending to drain into said port for accumulating a predetermined small amount of it on the hearth surface before allowing any of it to enter said port, but overflowing into said port when an excess of fluid fuel drains thereinto.

9. In the liquid fuel burning apparatus defined in claim 4, said discharge port being located toward the outer part of said hearth, and means supporting said hearth in such inclined relation as to cause liquid fuel to drain along said hearth surface into said port.

10. In a liquid fuel burning apparatus, a hearth apertured to accommodate a fuel projecting head and having a low level region toward which the

upper surface of said hearth slopes, said low level region being formed with a drain outlet port adapted to be coupled to a burner shut-off device, and a recessed hearth region about said drain outlet port in the path of liquid fuel tending to drain along said surface into said port for accumulating a predetermined small amount of said liquid fuel before allowing any of it to enter said port, but overflowing into said port when an excess of liquid fuel drains thereinto, said accumulated liquid fuel in said means being exposed to vaporizing heat and tending to burn off during normal operation of said apparatus.
